Inventor.

Isaac T. Pease

United States Patent Office.

ISAAC T. PEASE, OF THOMPSONVILLE, CONNECTICUT.

Letters Patent No. 72,672, dated December 24, 1867.

IMPROVED FIRE-ALARM.

The Schedule referred to in these Letters Patent and making part of the same.

TO ALL WHOM IT MAY CONCERN:

Be it known that I, ISAAC T. PEASE, of Thompsonville, in the town of Enfield, county of Hartford, and State of Connecticut, have invented a new and useful Improvement in Fire-Alarms; and I do hereby declare that the following is a full, clear, and exact description of the same, reference being had to the accompanying drawings, and to the letters of reference marked thereon.

Figure 1 shows a front view of the improved fire-alarm.

Figure 2 shows a top view of the same.

My invention consists in so constructing a self-acting fire-alarm, intended to be placed in any part of a building, that, by the unequal expansion of two metals joined together in strips, the increased temperature of a room in which a fire takes place shall operate in such a manner as to release a catch and give an alarm, by means of a common alarm-contrivance, or by ringing a bell.

A is the frame to which the different parts of the apparatus are attached. B B are the expansion-bar, composed of strips of iron and brass, or any other metals having unequal degrees of expansion by heat. The metal having the least expansion is placed upon the outside of the curve at B, so that a rise of temperature shall expand the inside of the curve more than the outside, and thereby causing the parts at b b to be further apart the higher the temperature. This causes the whole bar between C and n to be considerably lengthened by a slight rise in temperature.

One end of the bar B is fixed to the frame A at C, while the other end is free to move. To this free end is attached, by the nut n, a regulating-screw, S, which can be set out or in to let off the alarm at different temperatures. It also passes through a guide, g. Upon this screw rests the lever D, which has a nick, d, to hold the arm E of the hammer H, which strikes upon the alarm-bell F F.

G is a common alarm-movement, such as is ordinarily used in alarm-clocks. It is composed of a spring, I, which is wound up by a key, and a train of wheels, which act upon the hammer H as soon as it is released from the detent in the lever D. Upon one of the wheels of the train is the pin p, which operates the lever J, and raises it up to release the pin q from the arm K.

The axis L' carries the three arms K, L, M. L is an arm, to which a bell-wire can be attached to lead to any part of the building where it is desired to give the alarm. The arm M is connected by the link N to the spring O, which draws the arm M forcibly back when the arm K is released from the pin q. If it is desired to pull the arm L in the opposite direction, the arm M is attached by the link to the spring P instead of O.

The operation of my invention is as follows: The alarm is set by winding up the spring I, and setting the lever K so that it shall rest upon the pin q. The lever D is then placed in its proper position upon the screw S, the arm E being placed in the nick d, and the screw S adjusted to let off the lever at the desired temperature. This is done by a gauge introduced between the head of the screw and the nut n. When a fire occurs, and the temperature of the room rises to the height to which the apparatus is set, the bar D is released by the lengthening of the bar B B, and the alarm rings. The pin p pushes up the lever J, and releases the lever-arm K, so that M flies back by the action of the spring O, and pulls a bell or other alarm in a distant room.

What I claim as my invention, and desire to secure by Letters Patent, is—

1. The curved expansion-bar B, composed of two metals, of different rates of expansion by heat, and the adjustable screw S, when constructed and arranged substantially as herein described, for the purpose of a fire-alarm.

2. The combination of the bar B, the screw S, the alarm-movement G, the lever J, the levers K and L, or their equivalents, substantially as herein described.

ISAAC T. PEASE.
